SHEET CLAMP

Merrill G. Barker, Los Angeles, Calif.

Application December 24, 1940, Serial No. 371,477

12 Claims. (Cl. 85—5)

This invention relates to fastening devices, more particularly to devices for temporarily holding assemblies together while permanent fastening means such as rivets or other fasteners are applied.

In the fabrication of structures involving a large number of driven or headed fasteners, such as the sheet metal construction employed in aeroplanes, it is often necessary to provide some temporary fastening means for holding the sheets together and to adjoining structural members while rivets are being driven. Due to the extent of the parts held together, ordinary C clamps cannot be used, and recourse is had to the rivet holes and some means is provided for engaging the rivet holes and drawing the material together while it is being riveted. At the present time, the most common type of fastener for this purpose involves a body member having a pair of projecting elements one being slideable and engageable under the shoulder of the hole and which is drawn inwardly by a spring to cause the sheets to be drawn together. This type of holder requires special applying forceps, and in addition is extremely fragile as the projecting element, which is machined from the body member, often breaks off during use or application. The force which is available for drawing the sheet metal together is limited by the type of spring used to retract the sliding element and by the size of the body of the holder. Accordingly, there is a very definite limit upon the clamping force which can be made available in a holder of given size.

With the above considerations in mind, it is an object of the present invention to provide a temporary fastener which can be readily inserted without the use of special tools.

It is a further object of the present invention to provide a fastener which readily fastens in holes through different thicknesses of material.

It is a further object of the present invention to provide a fastener which will force the members being secured with sufficient compressive force to insure accuracy while riveting.

It is a further object of the present invention to provide a fastening element which can be readily adapted to holes of different diameters.

It is a further object of this invention to provide a fastening element which is always in position ready to insert in place.

It is a further object of the present invention to provide a holder which is rugged and not susceptible to breakage.

It is a further object of the present invention

to provide a holder which does not depend upon accurately machined surfaces for its efficiency.

It is a further object of the present invention to provide a holder, the work-engaging elements of which can be fashioned of wire of high tensile strength.

It is a further object of the present invention to provide a holder which automatically locks in place.

It is a further object of the present invention to provide a holder in which the work-engaging elements can be readily renewed.

It is a further object of this invention to provide a device which will align the holes on the material being clamped during the clamping operation.

This invention possesses many other advantages and has other objects which may be made more easily apparent from a consideration of one embodiment of the invention. For this purpose there is shown a form in the drawing accompanying and forming part of the present specification. This form will now be described in detail, illustrating the general principles of the invention; but it is to be understood that this detailed description is not to be taken in a limiting sense, since the scope of the invention is best defined in the appended claims.

Referring to the drawing:

Figure 1 is a side elevation of one form of a device embodying the present invention shown inserted in the work but in unclamped position;

Figure 2 is a top plan view of the device shown in Figure 1;

Figure 3 is a vertical sectional view taken along line 3—3 of Figure 2 showing the device in clamped position, and also showing in dot and dash lines the parts in another stage of operation; and

Figure 4 is a transverse section taken as indicated by line 4—4 of Figure 3.

It is proposed in the present device to provide a clamp which, after insertion, and while the material is being clamped, will first align the holes and then clamp the sheets together. Accuracy of alignment can be secured in the usual type of sheet holding clamp only by making the clamp accurately fit the hole, which means that the machine work on such a clamp must be quite accurate and a large number of sizes of clamps must be provided to fit different sized holes. If accuracy of the clamp is depended upon to align the holes the clamp must be worked about in the holes in an effort to align the holes, and, as the material being clamped is often quite soft, such

treatment may bend the material or injure the edges of the holes. In order to accomplish the above aligning and clamping operation, the present construction is employed. Figure 1 shows the clamp in position in holes in two sheets which are in contact with each other but which are not accurately aligned. In Figure 3 the device is shown clamped, and it will be seen that the holes are now accurately aligned. This result is achieved by causing the two legs of the clamping element to spread as they slide relative to each other. The member 10 is intended to remain stationary in the device while the member 11 is mounted for sliding movement and is moved by means hereinafter described. Member 11 has a protuberance 12 near its outer end and beyond the protuberance it is provided with an extension 13. As member 11 is drawn upwardly the extension 13 striking the end of member 10 causes the members 10 and 11 to separate. This separation will, of course, align the holes. The holes being in proper alignment, further movement of the member 11 will cause the abutment of the protuberance 12 against the edge of the hole in the lower sheet and will clamp the two sheets together and thus prevent movement in any direction. The two members 10 and 11 are shown so separated in Figure 3. With this type of action it never becomes necessary to ream the holes after the clamp is withdrawn in order that the holes may be used for riveting purposes.

In order that the device be rugged and capable of manufacture without either the member 10 or 11 being accurately machined, it is proposed to make these members 10 and 11 of commercially available steel wire which has characteristics of durability and strength far surpassing any commercially available machinable material. It is also contemplated that the members 10 and 11 be readily replaceable in the clamp if one or the other be broken or bent under the vicissitudes of use. In the achievement of these and other results the operating mechanism shown has been devised. A body member 14 and a lever member 15 are provided and correlated with the rest of the structure so that movement of the lever member 15 with respect to the body member 14 causes motion of the locking stem 11 while the pilot 10 remains stationary, thus drawing the work against the body member 14, as above described. Body member 14 may be suitably constructed of sheet material bent to form a bearing surface 16 which is provided with an aperture 17 for the reception of the pilot and locking stem. This hole 17 should be slightly larger than the diameter of the wire utilized for the members 10 and 11 in order that the spreading of the outer ends caused by the extension 13 can cause the aligning of the holes in the work. It is further provided with an upwardly extending portion 18 suitably formed to be grasped by the fingers in causing relative movement between the lever 15 and the body 14. The lever 15 may be likewise constructed of sheet material bent into a channel shape for strength and to provide means for the attachment of pivots which are part of the operating mechanism. The lever 15 is pivoted to the body 14 by means of a stud or rivet 19 passing through the sides of the lever 15 and the body 14, respectively. The pivot 19 forms a satisfactory point of attachment for the pilot 10. This pilot may be formed of wire and have a loop 20 at one end thereof through which the pivot 10 can be inserted to hold the pilot in place. Renewal or replacement of the pilot thus in-

volves nothing more than the removal and replacement of the pivot 19. The pilot has been illustrated as being made of round material with its operating surface simply reduced to a semi-circular cross-section by grinding.

In order that the motion of the lever 15 cause motion of the locking stem 11 a link 21 is pivoted to the lever 15 and to a part of the locking stem 11. In the shown form the link 21 is illustrated as a channel having its flanges perforated for the reception of a pivot 22 which also passes through the flanges of the lever 15. The stem 11 is secured to the link 21 by simply having a portion 23 which passes through the flanges of link 21.

With the above construction, mere closing of the two members 14 and 15 will cause upward movement of the locking stem 11. However, it is desired that the device be capable of remaining closed when in clamping position, and further, that the device be capable of use in work of different thicknesses. In order to accomplish these results, the device is so constructed and arranged that upon closing movement the pivot 22 passes through a line drawn from pivot 19 to pivot 23. If this is done it can be readily seen that the device will tend to remain closed as the pivot 22 will have passed the dead center position. This result, however, can be achieved only if some means is provided for producing a tension on the pivot 23 in a downward direction. In order to produce this tension the coil spring 24 is made a part of the locking stem. When the device is closed to the position shown in the dot and dash lines in Figure 3 the protuberance 12 is against the bottom edge of the hole in the work and further movement of the lever 15 merely causes the spring 24 to be coiled, thus producing a clamping force on the work and at the same time permitting the lever 15 to be moved to the position shown in solid lines in Figure 3. As soon as the pivot 22 passes the above mentioned dead center the lever 15 snaps to the completely closed position shown in Figure 3. It will be realized, of course, that the provision of the coil spring 24 also permits this clamping action upon work of different thicknesses.

In order to be more certain of the position of the locking stem 11 an ear 25 may be formed from the material of which the body 14 is made, bent down to the position shown in Figure 3 and provided with a suitable opening to receive the stem 11. In order to provide a suitable bearing to take up the thrust of the link 21 while the device is being closed to clamping position the spring 24 may be allowed to ride upon the interior of the handle 18 of the body 14.

The above described device is completely operative, but in order to move the device from the position shown in Figure 3 to that shown in Figure 1 a spring 26 is provided which extends around the pivot 22 and engages the lever 15 and the link 21. This spring 26 causes the device to normally open, but is of insufficient strength to overcome the closing force exerted by spring 24 when the device is clamped in position in a hole. On the other hand, if the device is not inserted in the holes, closing of the lever 15 will not cause the spring 24 to be operated and thus the device, except when in place, always remains open. This is a great convenience in view of the large number of these devices used in a typical assembly operation.

I claim:

1. A hole engaging clamp comprising, a pair

of elements adapted to be inserted in a hole extending through the members to be clamped, means causing relative axial movement between said elements, and means causing separation of said elements upon such movement, whereby said elements are forced against the walls of the hole.

2. A hole engaging clamp comprising, a pair of elements adapted to be inserted in a hole extending through the members to be clamped with the end of one of said elements in advance of the other, means causing relative axial movement between said elements, and a projection on said one element engaging the other element upon such axial movement and causing separation of said elements to force them into engagement with the walls of the hole.

3. A hole engaging clamp comprising, a pair of elements of substantially semi-circular cross-section arranged with their flat sides opposed to each other and adapted to be inserted in a hole extending through the members to be clamped, means causing relative axial movement of said elements, and a projection on one of said elements engaging the other element upon such movement and causing separation of said elements to force them into engagement with the walls of the hole.

4. A hole engaging clamp comprising a pair of elements having opposed flat sides and curved hole engaging sides, and arranged with the end of one of said elements normally in advance of the end of the other for insertion into a hole extending through the members to be clamped, means causing relative axial movement of said elements to cause the ends of the two elements to pass each other, and a projection on the end of said one element for engaging the other element upon such movement, whereby to separate said elements and force them into engagement with the walls of the hole.

5. A hole engaging clamp comprising, a pair of elements having opposed flat sides and curved hole engaging sides, and arranged with the end of one of said elements normally in advance of the end of the other for insertion into a hole extending through the members to be clamped, means causing retrograde motion of said one element after insertion of said elements into the hole to cause the ends of the elements to pass each other, and a projection in that portion of said one element which is in advance of the end of the other, said projection engaging the other element upon such motion, whereby to separate said elements and force them into engagement with the walls of the hole.

6. A clamp for clamping sheets through holes therethrough comprising, a body, an element projecting from said body, means causing clamping action between said element and said body upon movement of said element toward said body, a lever on said body, and resilient means operatively connecting said element to said lever for motion upon movement of said lever but permitting yielding of said element with respect to said lever operatively connecting said element to said lever for such movement, said connecting means including resilient means.

7. A clamp for clamping sheets through holes therethrough comprising, a body, an element projecting from said body for insertion in holes in the sheets, means causing clamping action between said body and said element upon movement of said element toward said body, a lever pivoted to said body, and a link pivoted to, and

connecting, said lever and said element to cause motion of said element upon movement of said link in response to movement of said lever, the point of connection of said link and said lever passing through a line drawn between the pivot of the lever and the point of attachment of said link to said member in one stage of operation.

8. A clamp for clamping sheets through holes therethrough comprising, a body, an element projecting from said body for insertion in holes in the sheets, means causing clamping action between said element and said body upon movement of said element toward said body, a lever pivoted to said body, a link pivoted to, and connecting, said lever and said element, resilient means on said element permitting yielding of the pivotal connection of said link to said element with respect to the projecting portion of said element, the pivotal connection of said link to said lever passing through a line extending from the lever pivot to the pivotal connection of the link to the element at one stage of operation.

9. A clamp for clamping sheets through holes therethrough comprising, a body, an element projecting from said body for insertion in holes in the sheets, means causing clamping action between said element and said body upon movement of said element toward said body, a lever pivoted to said body, a link pivoted to, and connecting, said lever and said element, resilient means on said element permitting yielding between the pivotal connection of said link to said element and the projecting portion of said element, the pivotal connection of said link to said lever passing through a line extending from the lever pivot to the pivotal connection of the link to the element at one stage of operation, and spring means normally causing motion of said lever to project said element from said body, but ineffective to cause such motion after passage of said pivot connecting the link to the lever through the above mentioned line during clamping while said element is inserted in holes in sheets to be clamped.

10. A clamp for clamping sheets through holes therethrough comprising, a body, a pair of resilient elements projecting therefrom, one of said elements having its end normally in advance of the end of the other, said one element having a projection in the portion beyond said other element, means causing retrograde movement of said one element after insertion of said elements in the holes in the sheets, said movement causing clamping action between said projection and said body.

11. A clamp for clamping sheets through holes therethrough comprising, a body, an element projecting from said body for insertion in holes in the sheets, means causing clamping action between said element and said body upon movement of said element toward said body, a lever pivoted to said body, a link pivoted to the lever, a spring connecting said link to the projecting element and permitting yielding of said link with respect to the projecting element, and a guide on said body engaging said spring restraining its motion during clamping operation of the lever.

12. A clamp for clamping sheets through holes therethrough comprising, a body, a pair of resilient elements projecting therefrom, one of said elements having a projection thereon, means causing retrograde movement of said one element in the holes in the sheets, such movement causing clamping action between said projection and said body.

CERTIFICATE OF CORRECTION.

Patent No. 2,237,807.

April 8, 1941.

MERRILL G. BARKER.

It is hereby certified that error appears in the printed specification of the above numbered patent requiring correction as follows: Page 3, first column, lines 65, 66 and 67, claim 6, strike out the words "operatively connecting said element to said lever for such movement, said connecting means including resilient means"; and that the said Letters Patent should be read with this correction therein that the same may conform to the record of the case in the Patent Office.

Signed and sealed this 29th day of July, A. D. 1941.

(Seal)

Henry Van Arsdale,
Acting Commissioner of Patents.
